(57) **CLAIM**

We claim the ornamental design for a model vehicle assembly, as shown and described.

DESCRIPTION

FIG. 1 is an upper, left, front perspective view of a model vehicle assembly showing our new design;
FIG. 2 is a front elevation view thereof;
FIG. 3 is a rear elevation view thereof;
FIG. 4 is a left side elevation view thereof;
FIG. 5 is a right side elevation view thereof;
FIG. 6 is an upper plan view thereof;
FIG. 7 is a lower plan view thereof;
FIG. 8 is an upper, right, rear perspective view thereof; and,
FIG. 9 is a lower, right, rear perspective view of the model vehicle assembly.

In the drawings, the broken lines illustrate portions of the model vehicle assembly that form no part of the claimed design.

1 Claim, 8 Drawing Sheets
